United States Patent Office.

THOMAS H. HAZARD, OF RICHMOND, VIRGINIA.

Letters Patent No. 100,760, dated March 15, 1870.

IMPROVED MEDICAL COMPOUND FROM CHLORAL.

The Schedule referred to in these Letters Patent and making part of the same.

To all whom it may concern:

Be it known that I, THOMAS H. HAZARD, of the city of Richmond, in the county of Henrico, and State of Virginia, have invented a new and useful Medical Compound, of which the following is a full and correct description.

My invention relates to the preparation of a medical compound of a hypnotic character, and is composed of the following ingredients combined in the following relative proportions, or others substantially the same.

To prepare two (2) ounces of my invention, which I shall call the Elixir of the Hydrate of Chloral, take eighty grains (80 gr.) of the hydrate of chloral, two drams (5ij.) of curaso, six drams (5vi.) of simple syrup, (syrupis simplex;) one dram (3l.) of brandy, (spiritus vini Gallici;) and seven drams (5vii.) of water, (aqua distillata.) Combine and dissolve these ingredients thoroughly together, and the compound is ready for immediate use.

The object of my invention is to produce a medicine the taste whereof shall not be repulsive, and its effect upon the system of a narcotic character, without causing the subsequent deleterious results attendant upon the administration of the usual opiates.

What I claim as my invention, and desire to secure by Letters Patent, is—

The elixir of the hydrate of chloral, compounded and prepared as herein described, or in a manner substantially the same.

In testimony that I claim the foregoing medical compound of elixir of the hydrate of chloral, as above described, I have hereunto set my hand and seal this 15th day of February, 1870.
